to Heywood-Wakefield Company, Gardner,
Mass., a corporation of Massachusetts

Application March 4, 1937, Serial No. 68,002

Term of patent 3½ years

To all whom it may concern:

Be it known that I, Herman E. Buchheim, a citizen of the United States, residing at Cambridge, in the county of Middlesex and Commonwealth of Massachusetts, have invented a new, original, and ornamental Design for a Desk or Similar Article, of which the following is a specification, reference being had to the accompanying drawing, forming part thereof, in which

Figure 1 is a perspective view of a desk or similar article showing my design; and

Figure 2 is a sectional view taken along the line 2—2 of Figure 1.

The essential features of the design, shown in full lines, consist of the pair of oppositely facing standards, with each standard being constituted by two members of round cross-section, having their upper vertical portions in side-by-side relation, said members at their lower portions bending outwardly at an obtuse angle and then downwardly to provide terminal foot portions in spaced relation.

I claim:

The ornamental design for a desk or similar article, as shown and described.

HERMAN E. BUCHHEIM.
